UNITED STATES PATENT OFFICE

CHARLES RYSTROM, OF ROCKFORD, ILLINOIS.

DESIGN FOR A HEEL FOR BOOTS OR SHOES.

SPECIFICATION forming part of Design No. 31,497, dated September 5, 1899.

Application filed July 24, 1899. Serial No. 725,018. Term of patent 14 years.

To all whom it may concern:

Be it known that I, CHARLES RYSTROM, a citizen of the United States, residing at Rockford, in the county of Winnebago and State of Illinois, have invented and produced a new and original Design for Heels for Boots or Shoes, of which the following is a specification, reference being had to the accompanying drawings, forming part thereof.

Figure 1 is an isometrical representation of a heel, showing my new design. Fig. 2 is a lengthwise vertical central section.

As shown in the drawings, the leading or material feature of my design consists of the heel in horseshoe shape, composed of the branches 1 and 2, the under face of the

branches being tapering, so that the space between them is greater at the outer face of the heel than at the inner face. The heel is thicker at the rear than at the front, being ²⁰ a gradual taper. Two concentric grooves 4 and 5 are formed in the outer face of the heel.

Having described my invention, what I claim as new, and desire to secure by Letters Patent, is—

The design for a heel for boots and shoes as herein shown and described.

CHARLES RYSTROM.
